UNITED STATES PATENT OFFICE.

A. WALDO ROCKWOOD, OF MELROSE, MASSACHUSETTS.

CORRUGATED TRIMMING AND PROCESS OF MAKING SAME.

Application filed December 18, 1925. Serial No. 76,846.

My present invention is a new and more desirable trimming to be utilized on automobiles, shoes, articles of clothing, and the like; and embodies the novel process of 5 fashioning same.

It is desirable, in the manufacture of automobile upholstery, shoes, girdles, garters, and many other articles, to have a crinkled or corrugated trimming which will have a 10 substantial amount of elasticity or stretch to it.

Heretofore, it has been customary to unite trimming material and an elastic base or goring by means of longitudinally extending 15 seams, stitching or the like, but this has not been satisfactory since the elasticity of the resultant article was limited by the stitching and not by the elasticity of the goring.

20 I have discovered that any desirable trimming material, leather, satin, silk, suede or the like, can be attached to the elastic goring by non-longitudinally extending securing means, thus enabling the resultant article to be stretched as much as desired, 25 dependent only on the limit of elasticity of the materials comprising it and not dependent on the uniting means. Preferably I carry out this invention by transverse stitching, 30 uniting the trimming and the elastic base, although any separate fastening means, such as staples or the like, will produce the same desirable result. Furthermore this transverse stitching predetermines the corrugations or crinkling into which the resultant 35 article will contract upon completion of the fastening and release of the tension.

The object of my invention is to provide 40 an attractive and symmetrical corrugated trimming, in which leather, suede, silk, satin, or any other desirable trimming material, is fastened to a base of elastic goring by devices which will not limit the elasticity of the goring. I have discovered that this 45 desirable result can be obtained by fastenings, such as transverse stitching. Thus the elastic material is held stretched under tension, and the material forming the finish,—leather, silk, etc., is secured to it so that, when 50 released, it automatically forms equally spaced corrugations, due to said transverse stitching, contrary to longitudinal stitching, which produces unequally spaced and irregular corrugations, also which limits the 55 stretch of the elastic base and causes the stitching to break upon changed direction

or too great a stretching. This novel transverse stitching produces equally spaced and regular corrugations, while in no way limiting the stretch of the elastic base, and furthermore forms securing means, such as 60 stitches, which are not affected by changes in direction, stretching the goring to its limit, or around corners. Thus my present invention of transverse securing devices 65 creates a firm, attractive, symmetrical, and novel trimming.

In the accompanying drawing,

Fig. 1 is a perspective view of a section of the facing material stitched transversely 70 to the elastic base, while held stretched under tension;

Fig. 2 is an enlarged perspective cross sectional view showing the equally spaced corrugations formed on the facing material 75 upon releasing the tension;

Fig. 3 is a perspective view of the corrugated trimming as it appears when a finished product.

Referring to said drawing, 1 designates 80 the facing material which may consist of leather, suede, silk, satin, or any other desirable finishing or trimming material, held to the elastic goring 2, used as a base, by transverse stitching such as are shown at 3. 85

As clearly illustrated in the drawings, the elastic base or strip 2 is held under tension while the facing material 1 is applied and stitched or secured thereto. Upon completion of the securing or attaching of the facing 90 1 to the strip 2, the tension on the strip 2 is then released, allowing the elastic strip 2 to retract to its normal capacity and thereby drawing the facing 1 into a series of even, 95 equally spaced corrugations, due to the transverse rows of stitching, as clearly shown in Figs. 2 and 3.

As described above, I have produced a new type of corrugated trimming, in which the transverse stitching makes possible 100 equally spaced corrugations adding to the ornamental value, and trimming which has the capacity for stretching unaffected and unlimited by the fastenings holding the trimming and goring together. 105

My invention is further described and defined in the form of claims as follows:

1. The improved process of forming corrugated trimming, which consists in placing 110 a strip of elastic material under tension, applying a strip of facing material thereto, uniting the two strips by rows of stitching

5 applied transversely thereof at predetermined substantially equally spaced intervals throughout the length of said strips, and then releasing the tension on the elastic strip, whereupon, on return of the elastic material to untensed position, a trimming will be produced, having a facing with a plurality of substantially equally spaced corrugations transversely thereof, which corrugations are formed by the predetermined substantially equally spaced transverse rows of stitching.

10 2. As an article of manufacture, a corrugated trimming, comprising a strip of elas-

tic material and a strip of facing material 15 united by rows of stitching applied transversely of the two strips and at predetermined substantially equally spaced intervals throughout the length thereof while the elastic material is under tension, each corrugation being formed by said predetermined substantially equally spaced rows of transversely applied stitching upon return of the elastic material to untensed position.

20 25 In testimony whereof, I have signed my name to this specification.

A. WALDO ROCKWOOD.
